LENS HOUSING

Harry T. Bannister, Huntington Woods, Mich., assignor to Chrysler Corporation, Highland Park, Mich., a corporation of Delaware

Application August 18, 1949, Serial No. 4,573

Term of patent 7 years

(Cl. D48—32)

To all whom it may concern:

Be it known that I, Harry T. Bannister, a citizen of the United States, residing in the city of Huntington Woods, county of Oakland, and State of Michigan, have invented a new, original, and ornamental Design for a Lens Housing, of which the following is a specification, reference being had to the accompanying drawing, forming part thereof, in which:

Fig. 1 is a top plan view of the lens housing;
Fig. 2 is a side elevation of the lens housing, showing my novel design;

Fig. 3 is an end elevation thereof;
Fig. 4 is a vertical section taken on the line 4—4 of Fig. 2;

Fig. 5 is a section taken on the line 5—5 of Fig. 2; and

Fig. 6 is a perspective view thereof on a somewhat reduced scale, the dotted line showing of the portion of an automobile being for illustrative purposes only.

I claim:

The ornamental design for a lens housing, substantially as shown and described.

HARRY T. BANNISTER.
